United States Patent

Des. 241,422
Patented Sept. 14, 1976

241,422

COMBINED MOTORCYCLE FENDER AND TAIL LIGHT

Preston L. Petty, 403 N. Main St.; and Albert F. Harrel, 2409 Hawthorne Drive, both of Newberg, Oreg. 97132; and Gary M. Scott, 193 NW. Alpine, Dundee, Oreg. 97115

Filed Dec. 9, 1974, Ser. No. 530,857

Term of patent 14 years

Int. Cl. D12—11

U.S. Cl. D12—186

FIG. 1 is a perspective view of the combined motorcycle fender and tail light;

FIG. 2 is a side elevational view thereof;

FIG. 3 is a bottom plan view thereof;

FIG. 4 is a top plan view thereof;

FIG. 5 is a rear end elevational view thereof; and

FIG. 6 is a front end elevational view thereof.

We claim:

The ornamental design for a combined motorcycle fender and tail light, as shown.
